UNITED STATES PATENT OFFICE.

CHARLES LEFKOWITZ, OF NEWARK, NEW JERSEY.

CARBOY.

Application filed January 5, 1924. Serial No. 684,635.

To all whom it may concern:

Be it known that I, CHARLES LEFKOWITZ, a citizen of the United States, and a resident of Newark, in the county of Essex and 5 State of New Jersey, have invented a new and Improved Carboy, of which the following is a full, clear, and exact description.

My invention has for its object to provide a carboy which may be constructed with a 10 limited amount of material, the construction being such that the carboy is of great strength to withstand shocks and strains.

Another object of the invention is to provide panels which are removably disposed 15 in the carboy, the panels having shoulder members, each shoulder member having a side forming with its outer face an acute angle, the said side on each shoulder member engaging a corresponding side on an adjacent shoulder member to prevent the inward movement of the panels in the carboy.

Still other objects of the invention are to provide a cushioning device at the bottom of the carboy and a cover having depending 20 means for engaging the carboy.

Additional objects of the invention will appear in the following specification in which the preferred form of my invention is described.

30 In the drawings similar reference characters refer to similar parts in all the views in which,—

Fig. 1 is a horizontal sectional view showing my improved carboy;

35 Fig. 2 is a sectional view on the line 2—2 of Fig. 1;

Fig. 3 is a fragmentary perspective view showing the arrangement of the panels with their shoulders disposed at each other;

40 Fig. 4 is a fragmentary view showing the upper portion of one of the shoulder members on the panels, and;

Fig. 5 is a view showing in elevation, one of the panels.

45 By referring to the drawings it will be seen that the body 10 of the carboy, which is illustrated in the drawings is octagonal in shape but it will be understood that this is not essential and that a carboy body may be 50 used of another shape.

In the bottom of the carboy body 10, there is disposed a cushioning device consisting of two parallel horizontal supporting members 11, connected at their underside by a member 12, the ends of the horizontal supporting members 11 being raised from the

bottom of the carboy by supports 13, these supports 13 being disposed between shoulder members of the panels which will shortly be described. Disposed at an angle to the horizontal supporting members 11, there are horizontal supporting members 14, these horizontal supporting members 14 being disposed above the horizontal supporting members 11 and having their ends raised from the bottom of the carboy body 10 by the supports 15. It will be seen that with this construction a bottle disposed in the carboy will rest on the horizontal supporting members 14 which will be reinforced by the horizontal supporting members 11 which are connected together by the member 12.

The sides of the bottle disposed in the body of the carboy are supported by the panels 16, each of these panels 16 having two shoulder members 17. As will be seen by referring to Fig. 1 of the drawings, the outer faces 18 of the shoulder members 17 engage the inner sides of the body 10, the outer sides 19 of the shoulder members 17 having faces which are disposed in planes extending substantially through the center line of the body, the said faces in the construction illustrated in the drawings being disposed at acute angles to the outer faces 18 of the shoulder members 17. As the shoulder members 17 engage each other at their face 19 this construction prevents the inward movement of the panels relatively to the body 10. The panels have horizontal supports for engaging the sides of the bottle, these horizontal supports 20 being secured to the shoulder members 17 as best illustrated in Fig. 5 of the drawings. In addition, the panels have bottom members 21, the ends of which are disposed in the cut-away portions 22 in the shoulder members 17, the bottom members 21 being secured to the shoulder members 17 and resting on the horizontal supporting members 11 and 14 to hold the horizontal supporting members 11 and 14 at the bottom of the body. In addition, the panels have top members 23 which have their ends disposed in the cut-away portions 24 in the shoulder members 17 and which are secured to the shoulder members.

These top members 23 of the panels are engaged by the depending shoulders 25 on the cover 26 and it will therefore be seen that when the cover is disposed in position on the body 10, that it will serve to hold the panels in position and it will also hold the

horizontal supporting members 11 and 14 in position. Secured to the depending shoulders 25 on the cover 26, there are bottle supports 27, these bottle supports 27 extending across the carboy and having their ends secured to the bottom of the shoulders 25, the supports 27 having cut-out portions 28 to fit the shoulder on the bottle.

10 The supports 13 and 15 fit between the shoulder members 17 as is illustrated in the drawings so that the lateral movement of the supports 13 and 15 is prevented by contact with the shoulder members 17.

15 Having thus described my invention what I claim as new and desire to protect by Letters Patent is:

20 1. In a carboy a body, a plurality of panels in the body, each panel having two shoulder members one at each side, each shoulder member having an outer side forming with its outer face an acute angle, each shoulder member at each outer side engaging the outer side of a shoulder member on an adjacent panel to prevent the inward movement 25 of the panels.

25 2. In a carboy a body, a plurality of panels in the body, each panel having two shoulder members one at each side, each shoulder member having an outer side extending in a plane passing substantially through the center of the carboy, each shoulder member at its outer side engaging the outer side of a shoulder member on an adjacent panel to prevent the inward movement of the panels.

30 3. In a carboy a body, having sides disposed at angles to each other, a plurality of panels in the body, each panel having two shoulder members one at each side, each shoulder member having an outer face engaging a side of the body and an outer side having a face engaging the face on the outer side of a shoulder member on an adjacent panel.

35 4. In a carboy a body, two panels in the body, each with a shoulder member, the shoulder members having faces which engage each other to prevent the inward movement of the panels at the shoulder members.

40 5. In a carboy, a body, two horizontal supporting members spaced apart at the bottom of the body, supports for the ends of the members and means secured to the members

and connecting them together between their ends.

6. In a carboy a body, two horizontal supporting members spaced apart at the bottom of the body, supports for the ends of the members, means connecting the members together between their ends, an additional horizontal supporting member disposed at an angle to the first mentioned supporting members to engage the latter and supports for the ends of the said additional horizontal supporting member.

7. In a carboy a body, panels in the body, each having two shoulder members, a horizontal supporting member at the bottom of the body, two supports for the horizontal supporting member each disposed between and at two of the shoulder members to be held in place by the latter.

8. In a carboy a body, panels in the body each having two shoulder members, a plurality of horizontal supporting members disposed across each other at the bottom of the body and supports for the horizontal supporting members, each disposed between and at shoulder members to be held in place by the latter.

9. In a carboy an octagonal body, eight panels in the body one adjacent each of its sides, two shoulder members for each panel each shoulder member having an outer face engaging a side of the body and an outer side, the surface of the outer side of each shoulder member engaging a corresponding surface on the outer side of an adjacent shoulder member.

10. In a carboy, a body, panels in the body for supporting the sides of a bottle which may be disposed in the body, a cover for the body and dependent shoulders on the cover, the bottoms of which normally engage the top of the panels to hold the latter in place.

11. In a carboy a body, horizontal supporting members at the bottom of the body, supports for the horizontal supporting members, panels having members engaging the horizontal supporting members to hold the latter in place, a cover for the body and depending shoulders on the cover for engaging the panels to hold the panels down.

CHARLES LEFKOWITZ.
